UNITED STATES PATENT OFFICE.

ARTHUR H. PITNEY AND JACOB W. OGDEN, OF STAMFORD, CONNECTICUT, ASSIGNEES
TO PITNEY-BOWES POSTAGE METER COMPANY, OF STAMFORD, CONNECTICUT, A
CORPORATION OF DELAWARE.

PRINTING AND REGISTERING MECHANISM.

Original application filed April 5, 1922, Serial No. 549,734. Divided and this application filed December 9, 1926. Serial No. 153,568.

This case is a division of our application Serial No. 549,734, filed April 5, 1922, for printing and registering mechanisms (Patent No. 1,680,113 Aug. 7, 1928), and is filed 5 in compliance with official requirements for division of the aforesaid application.

This invention relates to a machine designed for use by persons, firms or corporations having a great number of letters or 10 packages to mail, to enable such users of the mail to buy any desired amount of prepaid postage from the Government, and print such amount of stamps by this machine in any quantities that they desire, from time to 15 time, until the total amount of postage which they purchased is exhausted; at which time the machine will automatically become locked so that no further stamps can be printed thereby all as fully explained in our aforesaid 20 patent.

We will explain the invention with reference to the accompanying drawings which illustrate one practical embodiment of the invention, which, however, is capable of 25 changes in form, construction and combinations of parts within the scope of the invention. An understanding of said machine will enable others to adopt and use the invention for various purposes within the scope of the 30 claims, which set forth the essentials of the invention and the novel features of construction and novel combinations of parts for all of which protection is desired.

In said drawings:

35 Figure 1 is a side view of the complete machine;

Figures 2 and 3 show an enlarged sectional elevation of the printing member operating devices, and the impression member.

40 The machine as shown in the drawings comprises (1) a suitable base or support on which is mounted the printing means, comprising an adjustable stamp carrier containing a multiple of stamp carrying dies or members and means whereby any one of such members can be operated when properly positioned at the printing point; (2) means for feeding a strip of paper past the printing point; (3) a meter containing registering mechanism 45 adapted to be operated by the mechanism which operates the stamp and paper feeding devices when the machine is in condition for operation, and to register the money value 50

of the stamps printed by the machine, when the machine is adapted for use as a postage 55 meter, in accordance with the value of the stamp printed.

The printing means and meter are mounted upon a base plate 103 which is fastened to a top 1 of a suitable hollow supporting member or trough 2 which is mounted upon a suitable floor stand 3 and supports the operative parts at about the height of an ordinary table in convenient position for manipulation by the operator. The meter 200 is also 60 detachably attached to this plate 103 beside the printing mechanism as hereinafter explained. The paper feeding devices are mounted upon the top 1 in proper relation to the printing devices; and the main operating mechanism 65 and the trip devices controlling the operations of the machine are preferably arranged beneath the plate 1 within the member 2.

The printing mechanisms are principally mounted on and in a boxlike casting 102, the 75 open bottom side of which is completely closed by the plate 103, which plate projects a sufficient distance in front of the casting 102 to form a seat for the meter. All these parts are fully illustrated and explained in 80 our aforesaid patent. The base plate 103 is secured to the casting 102 by screws and dowels, Figure 3, and is sealed so that no unauthorized person can remove it without leaving plain evidence of tampering. The whole 85 unit after assembly is slid in ways planed in the table 1 and fastened by screws from underneath. The table 1 is locked by a padlock to the trough 2 so that it can only be lifted by the holder of the key, who should be a responsible person.

It is not intended that the printing means shall be frequently removed from the machine, but if on demand it should be necessary to check it up with its meter it will be 95 easily detached, if mounted in a slide similar to the meter. Taking it off the machine does not give access to the internal mechanism however, for it is still sealed by one or more of bottom cover screws 130, above mentioned. 100

The printing devices.

In the construction shown in the drawings the printing mechanism comprises a plurality of printers or dies one for each denomination of stamp used in the machine mounted 105

on a rotatable support. These stamps are mounted on vertical spindles journaled in a rotatable member 100 which may be conveniently formed of suitable castings.

5 The part 100 carrying the printers or dies is fitted on a cylindrical standard rising from the top of the supporting casting or box 102 hereinafter more fully described.

The printers or dies P may be of any suitable kind. As shown they comprise a sleeve 115 having a radial projection on the peripheral face of which appears the desired printing surface; as indicated in the drawings. Each printer is mounted on a die shaft 112 which has projections or keys 112A on its opposite sides. These keys are turned off at the upper end where the shaft is journaled in the upper bearing 114. A flanged sleeve 112B fitting over and enclosing the keys, acts 20 as a journal for the lower end of the shaft 112 and runs in the bearing 113. At the extreme lower end of the shaft 112 a flanged collar 112C is securely pinned; its lower end passing through the plate 101 is slotted to fit 25 the tongue of an "Oldham" coupling 108. The flanged upper end of the collar 112C bears against the flange of the sleeve 112B on one side and against the inner side of the plate 101 on the other preventing any vertical 30 motion of the spindle 112. The printer die 115 is key slotted to fit the keys 112A on die shaft 112, and with the spacing collars 115A and 115B occupies all the space between the upper and lower bearings 114 and 113.

35 Each die or printing member is provided with suitable inking means, which may be of any suitable kind, but are preferably constructed as explained in our aforesaid patent.

A spring catch 125, Figs. 1 and 2, is mounted 40 on the case 102 and can be engaged in any one of the notches 100F cut on the rim of the rotating head 100, so that any one of the several dies may be correctly alined, with the shaft 104 in the base or in printing position. 45 There is one notch 100F for each printing member or die, and one extra notch is provided and so located that when it is engaged by the catch 125, none of the dies will be in printing position. It is only when the head 100 is 50 set in this neutral or ineffective printing position that the meter can be removed, as herein-after described.

To bring any printer to printing position, the head 100 is turned until the clutch member 112C of the desired printer registers with the clutch member 108, then it can be operated by power transmitted to such member 108.

55 As shown, member 108 is part of so-called "Oldham" coupling, the other member of which is connected to the upper end of a shaft 104 vertically mounted within the box casting 102, said shaft being driven by mechanism below the table 1, as explained in our aforesaid patent.

The upper end of shaft 104 is larger in diameter where it is journaled in the upper part of the base casting 102 and its upper end is provided with a tongue to fit the "Oldham" coupling 108. Shaft 104 is journaled 70 near its lower end in a bracket 102B in the box 102.

A small counter 116 is mounted on each overhead arm 100A of the rotating head 100 and operatively connected to the adjacent die 75 spindle 112. It registers every revolution of the adjacent die and is introduced as a check on the meter. This counter is made with an extra long spindle 116A, Fig. 24. The die shaft 112 has a hole 112D drilled through its 80 entire length and a smaller cross hole 112E drilled near the bottom end at a point which is covered by the sleeve 112B. The counter is securely fastened to the bracket 100E of the overhead arm 100A so that its spindle 85 116A passes through the hole 112D in shaft 112. A cross hole is drilled in counter spindle 116A in line with cross hole 112E of counter shaft. A small pin 117 is passed through both 112 and 116A which forces the 90 spindle 116A to revolve with the shaft 112. The pin 117 cannot come out as the sleeve 112B surrounds the hole 112E. The object 95 of carrying this fastening down into the body of the mechanism is to make it impossible to break the connection without having access to the interior of the machine, and this is prevented by the locks.

The impression devices.

100

Above the table 1 and suitably placed to produce impressions from the die that happens to be in printing position is mounted an impression member which may be of any suitable kind and construction, adapted to 105 cooperate with the printer in making the impressions when paper or mail matter, etc. is forced therebetween. As shown the impression member comprises a sector 4, which is provided with a recess in its outer face in which is secured a preferably rubber faced block 4A, whose rubber face 4B is molded to 110 conform to the circumference of the sector 4 and provides the resiliency necessary for producing a clear impression from the printing surface on the printer. These parts are fully described in our aforesaid patent.

The registering mechanism is contained in what we term the meter; and in the preferred form of the machine this meter is bodily attachable to and detachable from the machine; and mechanism is provided whereby when the meter is properly positioned in the machine it is automatically operatively connected with the printing mechanism and will register the amount of each and every stamp printed no matter in what order or sequence the stamps are used or how frequently the stamps are changed in the machine. This registering mechanism however forms no 125 130

part of the invention covered in this application and therefore needs no illustration or explanation herein.

The drawings accompanying this description are for the printing upon strips but obviously can be readily adapted for printing upon letters, checks, tickets and the like. That is, such machines will be equipped with the same "meter" and revolving set of printers or dies and the same connections, (locks and other safeguards) between the two. The only essential difference being that one machine prints directly on the letter and the other prints on tape to be attached to bulky packages that cannot be handled by the machine.

It will be obvious that this invention is not confined to the number of printers or dies, or the denominations indicated, but can be modified or simplified as conditions might require, without departing from the basic principles of the invention.

We claim:

1. In mechanism of the character specified, a rotatable shaft having a bore, a bearing for said shaft, a counter fixedly mounted adjacent one end of the shaft and having a

spindle extending into the bore of said shaft, and means fastening the spindle to the shaft at a point within the bearing of the shaft. 30

2. In mechanism of the character specified, a rotatable tubular shaft, a bearing for said shaft, means for rotating the shaft, a relatively fixed counter adjacent one end of the shaft and having a spindle extending into the shaft and means fastening the spindle to the shaft at a point within the bearing, said connection being inaccessible unless the shaft is removed from the bearing. 35

3. In mechanism of the character specified, a tubular shaft, a bearing for said shaft, a printer thereon, means for rotating the shaft and printer, a relatively fixed counter adjacent one end of the shaft and above the printer, said counter having a spindle extending 40 into the shaft and below the printer, and a pin fastening said spindle to said shaft at a point within the bearing whereby said fastening is rendered inaccessible until the shaft is removed from the bearing. 45

In testimony that we claim the foregoing as our own, we affix our signatures.

ARTHUR H. PITNEY.
JACOB W. OGDEN.
